SHUTTLE

John Kyle Dudley, Philadelphia, Pa.

Application November 20, 1943, Serial No. 511,135

8 Claims. (Cl. 139—199)

This invention relates to shuttles for use in looms adapted for weaving tapes, webbings, ribbons or other narrow textile fabrics.

The present invention is applicable to narrow fabric loom shuttles of either the fly type or the rack and pinion type; and to shuttles adapted to travel in either rectilinear paths or in arcuate paths, as determined by the guideways formed on the shuttle blocks of the loom.

One object of the present invention is to provide a shuttle which will be capable of carrying a large-capacity bobbin, and particularly a bobbin of the single-headed type, which can be wound on a conventional automatic winding machine, whereby stoppages of the loom for replenishing of the filling thread supply in the shuttle will be reduced to a minimum, and whereby the cost of winding bobbins for use in the shuttles of narrow fabric looms will be considerably reduced, as compared with the cost of winding bobbins for the shuttles of narrow fabric looms under current practices.

Another object of the invention is to reduce the size of a narrow fabric loom shuttle in the direction perpendicular to the plane of the face of the shuttle blocks, while at the same time increasing the thread capacity of the shuttle, whereby the center of gravity of a loaded shuttle will be moved in closer toward the vertical center of the guide or track in which the shuttle reciprocates, to reduce the friction and wear of and between the shuttle and guide which normally results from the leverage and weight of that portion of the shuttle and its load which overhangs the face of the shuttle blocks, and whereby the speed of the loom may be increased with a consequent increase in the hourly production of the loom.

Another object of the invention is to replace the low-capacity rotating bobbin, and its complementary brake spring, from which the filling thread is drawn tangentially, by the aforesaid large-capacity non-rotating single-headed bobbin from which the filling thread may be drawn axially over the headless end thereof.

Another object of the invention is to replace the troublesome take-up and tensioning springs currently used in narrow fabric shuttles with a simple and efficient means for snubbing the filling thread as it is drawn from the shuttle, whereby the tension on the filling thread, as it is laid in each open warp shed of the fabric by the shuttle, will be under uniform tension, and whereby the fabric produced will be of a uniform weave, width, thickness, and weight, and provided with straight uniform selvedges.

Other objects and advantages of the present invention will become apparent through the following description and by reference to the accompanying drawing of which:

5 Fig. 1 is a front elevation of a shuttle constructed and equipped in accordance with the present invention;

Fig. 2 is a plan view of the shuttle shown in Fig. 1 with the upper bow spring removed;

Fig. 3 is a longitudinal sectional elevation taken on the line 3—3, Fig. 2; and

Fig. 4 is a transverse sectional elevation taken on the line 4—4, Fig. 2.

The shuttle 1 is adapted to be composed of wood, plastic or other suitable material. The shuttle 1 includes a base portion 2 in the upper side of which is formed an arcuate or rectilinear groove 3, for reception of aligned tongues of contiguous upper guide blocks of the loom. The under side of the base 2 is provided with a guide groove 4 for reception of the tongues of lower guide blocks and which, in the case of the rack and pinion shuttles, is also provided with gear teeth 5 for engagement with the driving pinions of the loom, by which the shuttle is reciprocated in an arcuate or rectilinear path, as the case may be, through the open warp shed of the fabric being woven.

At its opposite ends, integral with and projecting outwardly from the base 2 of the shuttle 1, are end parts or pillars 6 and 7 respectively. The outer ends of the end pillars 6 and 7 are connected by a bridge member 9, said base, said end pillars, and end bridge member collectively defining a substantially rectangular opening 10 in the body of the shuttle, and in which a single-headed bobbin 11 is adapted to be supported.

40 The bobbin 11 includes a single circular end flange 12, and an integral axial quill 13, on which the body or bulk of the filling thread x is wound. The bobbin 11 is held in a stationary position, within the recess 10 of the shuttle 1, by the single circular head flange 12 of the bobbin snugly fitting into a U-shaped undercut groove 14 formed in the pillar 6 at the one end of the shuttle.

45 The pillar 6 is also provided with a complementary straightaway groove 15, in which is mounted a flat arched spring 16. The spring 16 is secured at one of its ends in the groove 15 by a screw or other fastening means 17, and is adapted to frictionally engage the outer end surface of the single head 12 of the bobbin 11.

50 In axial alignment with the bobbin quill 13, the pillar 7 is provided with a guide eye 18 which is set in an internal groove or recess 19 formed on

the inner face 20 of the pillar 7, whereby the outer end of the guide 18 does not project into the recess 10 of the shuttle beyond the inner face 20 of the pillar 7, thus providing a larger unobstructed recess 10 for the reception of the large-capacity bobbin 11.

The filling thread $x1$, as shown in Figs. 2 and 3 is drawn from the thread supply $x2$ axially of the bobbin 11 over the headless end thereof through the guide eye 18 in the pillar 7, from which the thread $x1$ is roved through a series of porcelain or other wear-resisting eyes or bushings 22, carried in suitable openings formed in the bridge 9, to effect a snubbing action of variable intensity depending upon the number of bends placed in the thread $x1$ between the eye 18 and the bushing 22 through which the thread is drawn before it leaves the shuttle in the course of weaving.

In order to insure easy slipping of the shuttle between the threads of the open warp shed, the opposite ends of the base 2 and the outside ends of pillars 6 and 7 are tapered to a substantially sharp edge 23. Bow springs 24, 24 are also provided adjacent the opposite sides respectively of the base 2 with their opposite ends anchored in the pillars 6 and 7 respectively.

The U-shaped anchored groove 14 for the bobbin 11 is formed in the sides and bottom wall of a similarly U-shaped recess 25 with the side and bottom walls, intermediate the U-shaped groove 14 and the end wall 26 of the bobbin recess 10, beveled, as indicated at 27 to receive the frusto-conical end $x3$ of the body x of the filling thread which lies immediately adjacent the single head or flange 12 of the bobbin 11.

The groove 15 in which the anchorage spring 16 is mounted is formed in the base surface 28 of the recess 25 straight across the width of the pillar 6.

By reason of the above construction and the construction of the pillar 7 with the guide eye 18 located in the recess 19 gouged out of the inner surface 20 of the pillar 7, a bobbin of maximum length and diameter may be used in the recess 10 in the body of the shuttle.

The recess 25 and groove 14 are open full width at their tops to permit the head 12 and adjacent end $x3$ of the bobbin 11 to be moved readily into and out of the shuttle.

I claim:

1. A narrow fabric loom shuttle having a bobbin-receiving recess formed between transverse end walls spaced apart longitudinally of the shuttle, one of said end walls having a complementary recess formed therein for receiving a disc-like head on one end of the bobbin, and a relatively thin-edged rib-like projection on said wall in a transverse plane intermediate said recesses and adapted to engage one face of said head between said face and an adjacent end face of a body of thread wound on said bobbin.

2. A narrow fabric loom shuttle having a bobbin-receiving recess formed between transverse end walls spaced apart longitudinally of the shuttle, one of said end walls having a complementary recess formed therein for receiving a disc-like head on one end of the bobbin, and a relatively thin-edged substantially U-shaped rib-like projection on said wall in a transverse plane intermediate said recesses and adapted to engage one face of said head between said face and an adjacent end face of a body of thread wound on said bobbin.

3. A narrow fabric loom shuttle having a bobbin-receiving recess formed between transverse end walls spaced apart longitudinally of the shuttle, one of said end walls having a complementary recess formed therein for receiving a disc-like head on one end of the bobbin, and a relatively thin-edged rib-like projection on said wall in a transverse plane intermediate said recesses and provided with an inwardly tapering edge adapted to engage one face of said head between said face and an adjacent end face of a body of thread wound on said bobbin.

4. A narrow fabric loom shuttle having a bobbin-receiving recess formed between transverse end walls spaced apart longitudinally of the shuttle, one of said end walls having a complementary recess formed therein for receiving a disc-like head on one end of the bobbin, a relatively thin-edged substantially U-shaped rib-like projection on said wall in a transverse plane intermediate said recesses and adapted to engage one face of said head between said face and an adjacent end face of a body of thread wound on said bobbin, and resilient means adapted to engage the opposite face of said head to force the first said face thereof into firm contact with said projection.

5. A narrow fabric loom shuttle having a bobbin-receiving recess formed between transverse end walls spaced apart longitudinally of the shuttle, one of said end walls having a complementary recess formed therein for receiving a disc-like head on one end of the bobbin, a relatively thin-edged substantially U-shaped rib-like projection on said wall in a transverse plane intermediate said recesses and adapted to engage one face of said head between said face and an adjacent end face of a body of thread wound on said bobbin, and a flat bow spring seated in the base of said complementary recess and engageable with the opposite face of said head to force the first said face thereof into firm contact with said projection.

6. A narrow fabric loom shuttle having a bobbin-receiving recess formed between transverse end walls spaced apart longitudinally of the shuttle, one of said end walls having a complementary recess formed therein for receiving a disc-like head on one end of the bobbin, a relatively thin-edged substantially U-shaped rib-like projection on said wall in a transverse plane intermediate said recesses and adapted to engage one face of said head between said face and an adjacent end face of a body of thread wound on said bobbin, and a flat bow spring seated in a groove formed in the base of said complementary recess and engageable with the opposite face of said head to force the first said face thereof into firm contact with said projection.

7. A narrow fabric loom shuttle having a bobbin-receiving recess formed between transverse end walls spaced apart longitudinally of the shuttle, one of said end walls having a complementary recess with a groove formed in the side walls thereof in a plane substantially parallel to said one end wall to receive the peripheral edge of a disc-like head on one end of the bobbin, said recessed end wall being beveled inwardly toward said groove around the marginal edges of said complementary recess to engage one face of the head of the bobbin between said head and a body of thread wound thereon.

8. A narrow fabric loom shuttle having a bobbin-receiving recess formed between transverse

end walls spaced apart longitudinally of the shuttle, one of said end walls having a complementary recess with a groove formed in the side walls thereof in a plane substantially parallel to said one end wall to receive the peripheral edge of a disc-like head on one end of the bobbin, said recessed end wall being beveled inwardly toward said groove around the marginal edges of said

complementary recess to engage one face of the head of the bobbin between said head and a body of thread wound thereon, said complementary recess having a rectilinear groove formed in its base, and a flat bow spring seated in said rectilinear groove to bear against the face of said head lying adjacent said base.

JOHN KYLE DUDLEY.
